(57) **CLAIM**

The ornamental design for a combination ceiling fan blade and blade attachment assembly, as shown and described.

DESCRIPTION

FIG. 1 is a perspective view from below of the combination ceiling fan blade and blade attachment assembly in accordance with my design, including the environment thereof;

FIG. 2 is a bottom plan view of the combination ceiling fan blade and blade attachment assembly in accordance with my design, on a reduced scale including the environment thereof;

FIG. 3 is a front elevation view of the combination ceiling fan blade and blade attachment assembly in accordance with my design, on a reduced scale including the environment thereof;

FIG. 4 is a perspective view from above of the combination ceiling fan blade and blade attachment assembly in accordance with my design;

FIG. 5 is a left side elevation of the combination ceiling fan blade and blade attachment assembly in accordance with my design;

FIG. 6 is a right side elevation view of the bottom side of the combination ceiling fan blade and blade attachment assembly in accordance with my design, turned upright for purposes of illustration;

FIG. 7 is a front end view of the combination ceiling fan blade and blade attachment assembly in accordance with my design; and,

FIG. 8 is a rear end view of the combination ceiling fan blade and blade attachment assembly in accordance with my design.

The broken line showing of environmental structure in FIGS. 1-3 is for illustrative purposes only and forms no part of the claimed design.
